[57] CLAIM

The ornamental design for an access flooring module for power and signal cables, as shown and described.

DESCRIPTION

FIG. 1 is a perspective view of the access flooring module showing our new design;

FIG. 2 is a front elevational view thereof the pattern which is partially shown on the coverplate is understood to repeat across the circumscribed area;

FIG. 3 is a rear elevational view thereof again the pattern which is partially shown is understood to repeat across the entire surface;

FIG. 4 is a top plan view thereof; and,

FIG. 5 is a side elevational view thereof the broken lines being for illustrative purposes only.

FIG. 1

FIG. 2

FIG. 3

FIG. 4

FIG. 5
